BURIAL VAULT

Max Skolnik, Chicago, Ill., assignor to Fibro-Mold Specialties, Inc., Chicago, Ill., a corporation of Illinois

Application June 13, 1941, Serial No. 397,924

4 Claims. (Cl. 72—7)

This invention relates to a burial vault and method of making the same.

Heretofore burial vaults were made of steel and of concrete which may or may not be reinforced. Concrete vaults, even though reinforced, are objectionable because of their appearance, their porosity, and because of their relatively great weight. Steel vaults are undesirable because they are subject to electrolysis and soon become rusted.

It is an object of the present invention to provide a light weight, inexpensive burial vault which is strong and unaffected by water, even for long periods of time.

It is a further object of the present invention to provide an economical method of making a waterproof burial vault which is light in weight and which has a highly decorative and pleasing appearance.

Other objects of the present invention will be apparent from the following description of the invention, which is illustrated by the accompanying drawing, in which:

Figure 1 is a perspective view of a vault embodying the present invention;

Fig. 2 is a plan view of a portion of the vault viewed from the line 2—2 of Fig. 1, and having portions broken away to show the construction of the cover portion of the vault;

Fig. 3 is an elevational view of the lower right-hand corner of the vault of Fig. 1, viewed from the line 3—3 of Fig. 1, and having portions removed to show the construction of the body portion of the vault;

Fig. 4 is a horizontal section through a corner portion of the vault taken on line 4—4 of Fig. 3, showing its construction; and

Fig. 5 is a sectional view on line 5—5 of Fig. 1, showing the construction of the cover, and showing the manner in which the cover cooperates with the body portion.

Referring more particularly to the drawing, wherein like parts are designated by like numerals of reference throughout the several views, a vault embodying the present invention has a boxlike body portion 2 and a cover portion 3, adapted to cooperate with said body portion and form a seal therewith.

The body portion comprises sides 4, ends 5, 50 and a bottom 6. Load-supporting side panels 4a, and panels 5a, and the bottom 6 are secured together in box-like form with the joints between said panels and between said panels and said bottom filled with a waterproofing material, such as

as bituminous material. A layer 7 of a hardened decorative cement, such as magnesium oxychloride cement, preferably reinforced by fibrous material such as asbestos fibers, as hereinafter described, covers the exterior of the panels and of the bottom. The layer is applied in plastic form and so it adheres to said panels. This layer 7 is stippled to provide a rough, rocklike outer surface 8, and a coating 9 of waterproof material, such as bituminous material or asphaltum, which is solid at ordinary temperatures, is applied over said cement to improve its water resistance and, if desired, a finish coat (not shown) of paint containing metal powder may be applied over the coating 9 to provide a pleasing metallic appearance if desired.

The side panels 4a, end panels 5a, and bottom panel 6a preferably contain a plurality of fibrous panel elements 10, fastened together to form a continuous solid fibrous panel base which is substantially coextensive with the respective side, end, or bottom. The panel elements are preferably of wood or other fibrous material adapted to receive metal fasteners, and they preferably have suitable tongue and groove side edges 11, although wooden lath are satisfactory. The panel elements in the side and end panels are preferably vertical and of substantially the same height as the height of said side panels. When the panel elements are wooden lath it is preferred that both vertical and horizontal lath be used and that the horizontal lath be spaced apart by about $\frac{1}{4}$ " or so. Means, such as corrugated metal fasteners 12, are provided for holding the panel elements 10 together so as to form a rigid supporting base for the panels.

The flat, rigid, supporting bases of the panels and of the bottom, consisting of a plurality of panel elements 10 solidly fastened together, have a contacting coating 13a of waterproofing material, preferably asphalt, over their entire surfaces, which coating partially impregnates the wood. A layer 13 of fiber-reinforced waterproofing material, such as tarred paper, tarred felt, and the like is attached to at least one side, and preferably to both sides, of the rigid supporting bases to form the load-supporting panels or bottom.

In the preparation of the body portion of the vault, the panel elements 10 may be cut to size and each joint dipped into waterproofing material, such as hot molten asphaltum or other bitumen, at about 210° F. The edges of the elements are then forced together and connected

with suitable fastening means, such as the metal fasteners 12, to form a rigid supporting base for each panel. The waterproofing material is then applied over the entire supporting base and, while the waterproofing material, such as bituminous material, is still in the molten stage, the sheet waterproofing material 13, such as tarred felt or tarred paper, is applied to each side of the panel base and rolled out, preferably with steam rollers, so that the panel has a smooth surface impervious to water. The side, end and bottom panels of the vault are then assembled in a boxlike form. Just prior to assembly, however, the lapping portions 15 are preferably coated with molten waterproofing material, so that the box formed by the panels is water-impervious.

The hardened decorative coating 1 is applied from a plastic cement composition, preferably magnesium cement, containing a substantial proportion of fibrous material, such as short fiber asbestos. In the application to the panels of the body portion the cement is preferably applied as two coats, the first thin coat being brushed or rubbed vigorously in contact with the sheet waterproofing material or asphalt, and the next coat being superimposed thereon to form a relatively thick layer 7. It is sometimes desirable that the second coat contain woven reinforcing material, and burlap, soaked with plastic magnesium oxychloride cement, is entirely satisfactory. During the setting of the cement the exothermic reaction causes softening of the asphalt and forms a firm bond between the panels and the layer 7.

If the rough or stippled surface 8 is desired, it may be produced by various methods known to those skilled in the art, and an outer waterproofing coating 9 may be conveniently applied by spraying molten asphalt over the stippled surface 8 of the hardened cement.

The cover has a peripheral frame 16 formed of sides and ends secured together and a shaped, central base portion 17, carried by said frame and extending completely over the window of said frame. A layer 18 of hardened cement which contains reinforcing members, preferably metal lath 19, suitably spaced therein, extends over said frame and said shaped portion, and adheres thereto. One or more layers 20 of cement reinforced by fibrous material, preferably burlap thoroughly soaked in a slurry of magnesium oxychloride cement, is superimposed over the metal reinforcing cement layer 18 and integrally adheres thereto. The burlap-cement coating serves to further increase the load-carrying capacity of the cover. A layer 21 of hardened cement, also preferably a magnesium oxychloride cement or other hydraulic cement, is applied over the reinforcing layers 20 and is preferably stippled to provide a rough decorative surface. The decorative surface of the outer layer 21 is generally coated with a thin layer of solid waterproofing material, such as tar, asphalt or other bituminous material which is solid at normal temperatures. Such waterproofing material markedly increases the water-resistance of the outer cement coatings and improves the life of the vault.

The frame 16 may comprise a peripheral rigid frame member 23, preferably of wood, with a covering or layer 24 of suitable fibrous reinforced cement, such as burlap soaked in magnesium oxychloride cement. The frame 16 preferably has a groove 25 in its lower face 28 and around its periphery to receive the tapered edges 29

of the body portion 2. The central base portion 17 has an inner surface member or sheet of fibrous waterproofing material 25, such as tarred felt, tar paper, or the like, and a stiffening member 27 of hardened plastic material, which is preferably burlap or fibrous materials which have been soaked in a magnesium oxychloride cement slurry and allowed to harden.

In the preparation of a cover embodying the present invention, the frame 16 is formed by fastening the wood frame members 23 together in a suitable manner, dipping them in a hot bituminous material, and wrapping them with burlap 24 previously soaked in a magnesium oxychloride cement slurry. The burlap is allowed to dry and harden and during the hardening period, exothermic reaction in the magnesium oxychloride cement causes melting of the bituminous material on the frame members 23 and the formation of a relatively solid bond between the burlap and the frame members.

The shaped central base portion of the cover is prepared by bending a suitable sheet of fibrous waterproof material, such as tarred felt, tarred paper and the like, in the desired shape to form the inner surface of the shaped central portion of the cover, and superimposing thereon at least one layer of a hardenable cement, such as magnesium oxychloride cement, which preferably contains burlap or other fibrous material in substantial amount. The hardenable sheet 27 may be prepared by soaking a sheet of burlap in magnesium oxychloride cement. It is spread over the layer 25 and allowed to harden in contact with the inner waterproofed surface layer 25 while the latter is held in the desired form. Upon hardening, it is found to bond to the tarred felt or tar paper 25 so that both layers are held in the desired form for the central shaped portion 40 of the cover 3.

The central base portion 17 comprising the inner surface member 25 and the stiffening sheet member 27 is then placed on the frame 16 and united therewith by suitable means. The metal reinforcing members 19, such as metal laths, are then placed over the entire upper surface of the frame and the formed base of the central portion. A plastic cement composition, preferably magnesium oxychloride cement containing fibrous material such as asbestos fibers, is then applied thereover and around the metal reinforcing members 19, and against the frame and the central base portion 17. During the hardening period, it firmly unites the frame with the formed central portion of the cover. A plurality of layers of burlap saturated with magnesium oxychloride cement is superimposed on the metal reinforced layer 18 to further stiffen the vault cover.

The hardened decorative layer 21 may be applied in plastic form over the external surface of the layers 20 and stippled to provide a rough appearance. A waterproofing coating 30 of normally solid bituminous material or the like is then sprayed over the external surface of the decorative coating 21 to render it entirely impervious to water. If desired, the asphalt coating 30 may also be sprayed with metallic paint to give the vault a metallic appearance.

The plastic decorative cement and the hardenable cements used in the preparation of vaults of the present invention are preferably of the magnesium oxychloride type, comprising essentially magnesium oxide, magnesium chloride and water, and a substantial amount of finely pul-

verized silica, together with some fibrous material to decrease the brittleness of the hardened material. This class of cements has been found to be particularly well adapted for adhering to meltable waterproofing materials, such as bituminous materials including asphalt and tars which are normally solid at room temperatures.

The burial vaults prepared as above described are of relatively low cost, are relatively light in weight, and have a very pleasing appearance. Even though the load supporting elements may be of wood, it would seem that they are protected at all times from contact with moisture, water, or other deteriorating elements.

Although several embodiments of the invention have been herein shown and described, it will be understood that numerous modifications of the construction shown may be resorted to without departing from the spirit of this invention as defined in the appended claims.

What I claim is:

1. A water-resistant burial vault having a box-like body portion and a cover portion adapted to cooperate with said body portion to form a leak-proof seal therewith, said body portion comprising load supporting end panels, load supporting side panels and a bottom secured together to form a box, a coating of hardened magnesium oxychloride cement over the outer surface of said box and adhered to said panels and to said bottom and a coating of waterproofing material over the exterior of said hardened cement, said load supporting panels having a solid fibrous panel base coated with a normally solid bituminous material and having superimposed on said coating and integral therewith at least one layer of tarred paper, said solid fibrous panel base having a plurality of vertically aligned wood panel elements secured together, said panel elements having a height substantially equal to the height of said panels, said magnesium cement being adhesively bonded to said tarred paper.

2. A water-resistant burial vault having a box-like body portion and a cover portion adapted to cooperate with said body portion, said body portion comprising load supporting end panels, load supporting side panels and a bottom secured together to form a box, a coating of hardened magnesium oxychloride cement over the outer surface of said box and adhered to said panels and to said bottom and a coating of water-

proofing material over the exterior of said hardened cement, said load supporting panels having a solid fibrous panel base coated with a normally solid bituminous material and having over said coating and adhering thereto at least one layer of bitumen-impregnated fibrous material, said solid fibrous panel base being a plurality of vertically aligned wood panel elements with tongue and groove sides secured together, said panel elements having a height substantially equal to the height of said panels.

3. A water-resistant burial vault having a box-like body portion and a cover portion adapted to cooperate with said body portion to form a leak-proof seal therewith, said body portion comprising load supporting end panels, load supporting side panels and a bottom secured together to form a box with joints between said panels and said bottom and sealed with thermoplastic waterproofing material, a coating of hardened cement over the outer surface of said box and adhesively bonded through said thermoplastic waterproofing material to said panels and to said bottom and a coating of waterproofing material over the exterior of said hardened cement, said load supporting panels having a waterproofed solid fibrous panel base coated with a normally solid waterproofing material and having superimposed on said coating and integral therewith at least one layer of sheet waterproofing material, said solid fibrous panel base having a plurality of vertically aligned wood panel elements secured together, said panel elements having a height substantially equal to the height of said panels and having tapered upper edges.

4. A water-resistant burial vault having a box-like body portion and a cooperative cover portion adapted to cooperate with said body portion to form a seal therewith, said body portion comprising load supporting end panels, load supporting side panels and a bottom secured together to form a box, a layer of hardened plastic magnesium oxychloride cement over the outer surface of said box adhering to said panels and to said bottom, said panels having a plurality of fibrous load supporting elements fastened together and coated on at least one side with thermoplastic waterproofing material and being bonded to said cement through said waterproofing material.

MAX SKOLNIK.
